JAIL DOOR MECHANISM

Application filed May 9, 1930. Serial No. 451,020.

This invention relates to jail-door controlling mechanism adapted for application to the sliding doors of a row of jail cells wherein, by the mechanism, any or all of 5 the doors may, from a common point be moved between open and closed positions and positively locked in either position.

Such general type of mechanism is shown in Patent Nos. 1,543,140, 1,587,810, 1,658,148 10 and 1,665,243, issued June 23, 1925, June 8, 1926, February 7, 1928 and April 10, 1928 respectively, all to John T. Whitehouse; and this invention comprises generally improvements in such mechanism.

15 Reference to these patents and particularly to the last identified thereof makes evident that such mechanism includes as its principal characteristic features a gap nut for each door movable between positions 20 corresponding to door-open and door-closed positions; at latch bolt carried by the door hanger and lowerable thereon to engage the gap nut so that the door must follow movements thereof; means such as a wedge bar 25 for elevating the latch bolt above the gap nut, whereby a pull bar with which all of the gap nuts are rigidly associated may be manipulated to move another door independent of that under consideration; and 30 means such as a lock bar engageable by the latch bolt when the door is fully opened or closed and when the latch bolt is raised to release the door from the gap nut, for locking the door in said position thereof.

35 When the door is thus locked by interengagement of the latch bolt and lock bar in say open position, and it is desired to close the door by the gap nut, and the wedge bar is lowered for the purpose of lowering the 40 latch bolt, it has been found that such unauthorized pressure may be exerted directly on the door in a direction of its sliding movement, that the latch bolt may be prevented from dropping to engage the gap 45 nut so that the latter may then move without moving the door; after which the pressure may be terminated, allowing the latch bolt to drop without engaging the gap nut, thus leaving the door open and unlocked.

50 It is the object of this invention to elimi-

nate the possibility of such a situation, and to this end to provide means for causing latch bolt releasing movement of the lock bar, when the wedge bar is set to lower the latch bolt and as the gap nut starts its movement from the corresponding position. More particularly the invention comprises 55 a dog associated with the gap nut, and tripper means associated with the lock bar and with the wedge bar; the tripper means including a trip pin arranged to be lowered into the path of the dog when the wedge bar is lowered to allow lowering of the latch bolt.

The exact nature of this invention together 60 with further objects and advantages thereof will be apparent from the following description taken in connection with the accompanying drawings, in which Fig. 1 is a view generally in elevation and partly in section 65 showing a partially open sliding jail door and operating mechanism therefor, the metal cover plate for this operating mechanism being removed that the latter may appear; Fig. 2 is generally an end elevation of 70 the same as looking from the right, Fig. 1; Fig. 3 is an enlarged view of parts appearing in Fig. 1 illustrating the preferred embodiment of this invention; Fig. 4 is a showing in end elevation of parts appearing in 75 Fig. 3 as viewed from the left Fig. 3; and Fig. 5 is a section as in the plane of line 5-5, Fig. 3.

With reference now to the drawings, 1 is a cell door carried by a hanger 2 having 80 wheels 3 rolling on ways 4 between door-open and door-closed positions. The ways 4 are within a housing 5 having a cover plate 6 removed to show the parts normally 85 enclosed. The door appears in Fig. 1 in mid position, movable to the right to close and to the left to open. A gap nut 7 is provided with wheels 8 for movement corresponding to the door movement upon suitable ways 9.

90 It will be appreciated that whereas only one door and its operating mechanism are shown, in an actual installation, embodying a row of cells, a number of doors will be found. Thus the shown gap nut 7 may be 95 one of a number of gap nuts, one for each

door, all mounted upon a pull bar 10 as indicated, whereby each gap nut may be given reciprocal movement corresponding to that of which its door is capable. The door 1 is 5 associable with its gap nut 7 to be actuated thereby, by a latch bolt 11 vertically slidable in a bracket 12 carried by the door hanger 2, the lower extremity of the latch bolt being in the plane of movement of a notch 13 provided on the upper face of the gap nut. 10

The bolt 11 is supported by a wedge bar 14 through a roller 15 running on the wedge bar. The wedge bar is adjustable with parallel motion to adjust the elevation of 15 the latch bolt 11. For this purpose one end of the wedge bar is supported on a roller 16 carried by a bracket 17, and provided with a cam 18; and the other end of the wedge bar is connected with the crank end of a link 19, the opposite end of which link is secured by 20 a bracket 20. By this means, referring to the showing of Fig. 1, a movement to the right of the wedge bar will cause its elevation and hence that of the latch bolt 11, regardless 25 of the position of the door 1. The specific means by which the wedge bar is shifted left and right and thus up and down is immaterial, but as shown comprises linkage including pull rod 21, bell crank 22, link 23, lever 24 and rod 25.

By such control means the latch bolt may be caused to assume any of its three principal elevations: lowermost, in which it will drop into the notch 13 of the gap nut to be 35 positively engaged for actuation in either left or right direction; uppermost, in which the gap nut is cleared entirely; and intermediate, in which the gap nut will engage the latch bolt to close the door but not open it. Fig. 1 shows the latch bolt in lowermost 40 position.

Oppositely extending within the housing 5 are a pair of lock bars 26 and 27 hinged at their adjacent end to a fixed bracket 28. 45 These lock bars provide detent means for locking the door in open and closed positions respectively, while the gap nut is moved to other positions as appears particularly in Patent No. 1,665,243 of April 10, 50 1928 to John D. Whitehouse. To this end the latch bolt 11 is provided with a dog 11a in the plane of the lock bar 26, and the lock bar is provided with a notch 29 located to engage the dog 11a when the door is in full 55 open position and the bolt 11 is raised to clear the gap nut 7. Similarly the lock bar 27 extends towards door-closed position to engage a projection associated with the bolt, to lock the door in closed position while the 60 gap nut is moved therefrom.

What has thus far been described is not new in the art. It will be noticed, however, that lowering of the latch bolt is not positive, but effected only by gravity. Thus it 65 has been found when the door is locked by

the lock bar 26 and the wedge bar 14 is lowered to allow release of the bolt from the lock bar and engagement thereof with the gap nut, it is possible to exert such pressure on the door in the direction of its movement 70 that the latch bolt will be retained in elevated position so that the gap nut may be moved without causing the intended corresponding door movement; whereupon release of this pressure allows the latch bolt to 75 drop clear of the lock bar, leaving the door free, and this without the knowledge of the rightful operator positioned at the end of the row of cells.

As stated it is the object of this invention 80 to prevent such a possibility. To this end a bell crank 30 is mounted on the pin 31 by which the crank end of the link 19 has its connection with the wedge bar 14. This bell crank has the arm indicated engaging 85 the pin 32 by which the link 19 is mounted on the bracket 20; so that the bell crank is caused to follow motions of the link. Loosely mounted on the bell crank 30 by means of the pin 33 is a vertical lever 34 extending above the wedge bar 14 and below the bell crank 30 as indicated. Obviously the lever 34 may have up and down parallel motion as the bell crank 30 moves about the pin 32, and the lever may also have pivotal 95 motion about the pin 33.

The upper extremity of the lever has connection, as by a chain 35 running over sheave 36 carried by the bracket 20, with the near and free extremity of the lock bar 26. Upon 100 the lower extremity of the lever 34 is secured a housing 37 having a vertical slot 38 in which a trip 39 is slidable, with movement limited by engagement of the pin 40 carried by the trip 39 and extending into the 105 opening 41 in the housing 37.

Secured upon the corresponding end of the gap nut 7 is a dog 42 into the path of movement of which the trip 39 projects when the wedge bar 14 is in its lowermost 110 position which is as indicated Fig. 3 in which the gap nut 7 is at its left-hand or door-open extreme position, the trip 39 being chamfered as indicated to allow the dog to ride therewith to arrive at the shown position.

Suppose now the parts as indicated, the wedge bar lowered to allow the latch bolt to drop to engage the gap nut, but the latch bolt actually maintained raised, engaged by 120 the lock bar, by unauthorized pressure upon the door. As the gap nut moves to the right, through engagement of the dog 42 with the trip 39, a counterclockwise motion is imparted to the lever 34, which through the chain 125 35 raises the lock bar 26 above the upper limit of latch bolt movement; which positively frees the latch bolt from the lock bar insuring lowering of the latch bolt by gravity in time to engage the gap nut, that 130

is, before the gap nut notch 13 passes the latch bolt.

Assuming now the wedge bar 14 raised to free the latch bolt from the gap nut, the bell 5 crank 30 moves clockwise about the bolt 32 to raise the lever 34 bodily, lower the free end of the lock bar 26 and raise the trip 39 clear of the dog 42. Thus locking engagement of the latch bolt with the lock bar is insured, and at the same time return movement to the right of the gap nut 7 without affecting the lever 34 and thus the lock bar, is permitted.

While this invention is actually shown applied to the lock bar 26 only it will be evident that it could as well be applied to the other lock bar 27 by which the door is maintained in closed position. It is more important of course to insure closing of the 20 door by the gap nut when intended, than it is to insure opening of the door; wherefore application of the invention to the door-open lock bar has been chosen for illustration.

25 What we claim is:

1. In an apparatus of the class described and including a sliding door, means for moving the same between open and closed positions and including a gap nut movable between corresponding positions and operator-controlled means for associating the door with said gap nut to cause the door to follow the gap nut movements, a lock bar for securing the door in one of said positions 35 when the door is released from said gap nut, and means adapted when the door is secured by said lock bar and the gap nut is in its corresponding position, to cause releasing movement of said lock bar upon 40 movement of the gap nut from its said position.

2. In an apparatus of the class described and including a sliding door, means for moving the same between open and closed 45 positions and including a gap nut movable between corresponding positions, a latch bolt arranged to be lowered to associate said door with said gap nut to cause the door to follow gap nut movements and operator-operated means for supporting said latch bolt in 50 adjusted positions to control said association, a lock bar engageable with said latch bolt when the door is in one of said positions and the latch bolt is elevated above said gap 55 nut, whereby the door may remain locked in said position while the gap nut is not in corresponding position, and cooperative means associated with said lock bar and with said 60 gap nut respectively and adapted to act as said gap nut moves from said corresponding position and when said operator-operated means is positioned to allow lowering of the latch bolt upon the gap nut, to cause movement of the lock bar to release the latch bolt 65

and thus insure engagement of the latch bolt with the gap nut.

In testimony whereof we hereby affix our signatures.

ARTHUR E. SHANK.
GOTTFRIED FISLER.
